UNITED STATES PATENT OFFICE

PETER PLANTINGA, OF GREENFIELD, MASSACHUSETTS, ASSIGNOR TO GREENFIELD TAP & DIE CORPORATION, OF GREENFIELD, MASSACHUSETTS, A CORPORATION OF MASSACHUSETTS

CONTROL MECHANISM FOR GRINDING MACHINES

Application filed September 30, 1930. Serial No. 485,473.

This invention relates to internal grinding machines and particularly to mechanism for controlling certain operations thereof.

It is the general object of my invention to provide improved control mechanism by which certain successive steps relative to internal grinding may be more effectively performed.

An important feature of my invention relates to the provision of means for effectively initiating a truing operation after the rough grinding of the work has been performed.

A further object of the invention is to provide mechanism for disengaging the feeding mechanism after the finish grinding is completed and for withdrawing the grinding wheel from the work.

My invention further relates to arrangements and combinations of parts which will be hereinafter described and more particularly pointed out in the appended claims.

A preferred form of the invention is shown in the drawings, in which

Fig. 1 is a sectional side elevation of the cross feeding mechanism of an internal grinding machine.

Fig. 2 is a sectional front elevation, taken along the line 2—2 in Fig. 1;

Fig. 3 is a detail front elevation of certain parts also shown in Fig. 2;

Fig. 4 is a detail sectional plan view, taken along the line 4—4 in Fig. 2;

Fig. 5 is a plan view of certain feed pawl mechanism, looking in the direction of the arrow 5 in Fig. 2;

Figs. 6 and 7 are front elevations of certain parts, looking in the directions of the arrows 6 and 7 in Fig. 5;

Fig. 8 is a sectional elevation of certain hydraulic actuating mechanism for the feed pawls, taken along the line 8—8 in Fig. 24;

Fig. 9 is a sectional end elevation, taken along the line 9—9 in Fig. 8;

Fig. 10 is a plan view of a transmitting member in the feed pawl mechanism;

Fig. 11 is an end elevation, looking in the direction of the arrow 11 in Fig. 10;

Fig. 12 is a sectional front elevation of certain control mechanism to be described;

Fig. 13 is an end elevation thereof, par-

tially broken away, and looking in the direction of the arrow 13 in Fig. 12;

Fig. 14 is a sectional side elevation of certain cam feeding mechanism, taken along the line 14—14 in Figs. 12 and 15;

Fig. 15 is a side elevation of the parts shown in Fig. 14, looking in the direction of the arrow 15 in said figure, and taken along the line 15—15 in Fig. 24;

Fig. 16 is a detail plan view, looking in the direction of the arrow 16 in Fig. 14;

Fig. 17 is a detail sectional plan view, taken along the line 17—17 in Fig. 14;

Fig. 18 is a sectional rear elevation, taken along the line 18—18 in Fig. 12;

Fig. 19 is a detail plan view, looking in the direction of the arrow 19 in Fig. 18;

Fig. 20 is a side elevation of a cam lever and clutch control parts, partly in section and taken along the line 20—20 in Fig. 21;

Fig. 21 is a side elevation, partly in section, of certain clutch and control mechanism for controlling the return feed of the grinding wheel;

Fig. 22 is a side elevation, partly in section, of additional control mechanism;

Fig. 23 is a detail sectional view, taken along the line 23—23 in Fig. 22;

Fig. 24 is a plan view, partly in section, of the assembled hydraulic control mechanism and the connection mechanism for actuating the hydraulic table valve of the grinding machine;

Fig. 25 is a detail front elevation, partly in section, and looking in the direction of the arrow 25 in Fig. 24; and

Fig. 26 is a detail sectional view of valve mechanism to be described.

I have shown my improvements embodied in an internal grinding machine of the general type disclosed in the prior patent to Drake, No. 1,662,240, issued March 13, 1928.

A form of control device suitable for controlling the hydraulic table mechanism in such a machine is shown and described in a prior Drake Patent No. 1,817,180, issued August 4, 1931.

Briefly described, the machine to which my improvements are applied is an internal grinding machine in which the work is sup-

ported in a large hollow or tubular work spindle which is mounted in a work head supported by a reciprocating table. The grinding wheel enters the work from the rear through the hollow work spindle and is relatively withdrawn rearward to engage a truing device mounted within the hollow spindle.

The grinding wheel is mounted for transverse or cross feeding adjustment radially of the work, and the work, as previously stated, is mounted for reciprocating axial movement relative to the grinding wheel.

Suitable provision is made for rotating the work and grinding wheel at desired speeds. The control devices of the machine are so designed that rocking of the control handle in one direction after the rough-grinding is completed will increase the table travel and effect relative rearward movement of the wheel and will also reduce the speed of table travel. This increased rearward travel carries the grinding wheel past the truing device and causes the wheel to be suitably dressed for the finish grinding operation.

As soon as the handle is released or restored to normal position, the table resumes its reciprocation between normal grinding limits but continues to travel at reduced speed until the finish grinding is completed.

Manual rocking of the control handle in the opposite direction then increases the table travel to withdraw the wheel a shorter distance from the work, restores the normal rate of table travel, and brings the table to rest with the wheel withdrawn so that the work may be removed and replaced.

My present invention relates more particularly to the provision of means by which the table control devices may be automatically or semi-automatically actuated, by which the cross feed may be automatically regulated for the different steps in the grinding operation, and by which the grinding wheel may be removed radially inward from the work when the grinding operation is completed.

Cross feeding mechanism

I will first describe briefly the mechanism for feeding the grinding wheel transversely toward or from the revolving work. Referring particularly to Figs. 1 and 2, a cross feed shaft 30 is mounted at its outer end in a fixed bearing 31 and is provided with a disc 32 fixed to said shaft and having a ratchet wheel 33 and ring gear 34 mounted thereon. The shaft 30 is effective to move the wheel slide through any usual operating connections or gearing not shown.

An outer flange 35 of the disc 32 also forms a gear engaged by a pinion 36 mounted in a hand wheel 37 and normally held from relative rotation therein. The pinion 36 may be turned manually by a handle 38 when relative adjustment of the hand wheel and disc 32 is desired. A cam ring 40 is mount-

ed on the hand wheel 37 and is moved angularly therewith.

A feed pawl 41 (Figs. 1 and 2) is fixed to a stud 43 pivoted in a pawl carrier 44 slidable on parallel rods 45. A second pawl 42 is loose on the stud 43. A spring 46 (Fig. 2) is connected to a stud 47 (Fig. 5) fixed in the pawl 41 and projecting loosely into an enlarged opening in the pawl 42. The spring 46 has a rearwardly projecting end 48 engaging the back edge of the pawl 42.

The pawls are so arranged that the point of one pawl is a half tooth to the rear of the point of the other pawl, so that a half tooth feed can be taken if desired. The carrier 44 is forced rearward or to the right in Figs. 2 and 5 by a coil spring 50 (Fig. 5).

An upwardly projecting arm 52 (Figs. 2 and 5) is formed as part of a bell crank 53 mounted on a pivot stud 54. The arm 52 engages the rear end of the pawl carrier 44 and the laterally projecting arm of the bell crank 53 is provided with a cam roll 55 engaging the cam ring 40 previously described. The cam is provided with steps or concentric portions at different distances from its axis, as clearly shown in Fig. 2, and the greater the radius of the cam step, the smaller return movement of the pawl carrier 44 will take place.

The limit of advance movement of the carrier is fixed and consequently the rate of cross feed is determined by the steps on the cam 40. Each cross feeding movement at the beginning of the grinding operation is fairly large, but the extent of movement is progressively decreased as the grinding approaches finish size.

Pawl carriage actuating mechanism

The mechanism for giving the pawl carriage or carrier 45 its feeding movement is best shown in Figs. 8 to 11. A rocker 57 (Fig. 10) is loosely mounted on the pivot stud 54 previously described and is provided with an adjustable contact screw 60 adapted to engage the rear face of the upwardly extending arm 52 of the bell crank 53 (Fig. 2).

A portion 61 (Fig. 11) of the rocker 57 is positioned above a stud 62 adjustably secured in the upper end of a piston rod 63 (Fig. 8) connected to a piston 64 yieldingly pressed downward in a cylinder 65 by a coil spring 66.

A pipe 67 (Fig. 8) is connected to the lower end of the cylinder 65 below the piston 64 and the pipe 67 is connected at its opposite end to ports 68 and 69 in a valve casing 70. A piston valve 71 is slidable in the casing 70 and is connected by a rod 72 and arm 73 to a lever 74 and cam roll 75 positioned for engagement by a cam block or dog 76 adjustably secured to the side of the table T. The valve casing 70 is provided with an

inlet 77 for a suitable pressure fluid and with an outlet or exhaust 78.

When the table T approaches its limit of travel in a given direction, the dog or cam block 76 depresses the lever 74 and connects the port 68 to the inlet pipe 77. Fluid under pressure is thus admitted under the piston 64, raising the contact screw 62 and swinging the rocker 57 to advance the feed pawls and turn the cross feed shaft any predetermined amount.

As soon as the piston 71 is released, a coil spring 79 (Fig. 8) returns the piston to the position shown in Fig. 8, with the port 69 connected to the exhaust 78. A suitable bleed opening 80 is provided in the side of the cylinder 65 to take care of any leakage past the piston 64.

During the normal operation of the machine, the feed pawls are thus actuated hydraulically by mechanism controlled by the table dog 76, but the extent of each feeding movement is controlled by the cam ring 40.

Automatic control mechanism

I will now describe the mechanism by which the sequence of operations of the machine is automatically controlled.

Referring particularly to Figs. 2, 12 and 13, a disc or plate 82 (Fig. 12) is provided with a hub portion 83 which is rotatably supported on a stud 84 fixed in a frame member 85 and standing perpendicular to the axis of the cross feed shaft 30.

The disc 82 is frictionally held from accidental movement by a friction collar 85 keyed to the end of the stud 84 and forced yieldingly against the outer side of the plate by a spring 86 seated in a recess in a cap or nut 87. A ratchet wheel 88, a cam plate 90 and a second cam plate 92 are all fixed to the plate 82 and are rotatable therewith.

A yoke 94 is loosely mounted on the hub 83 between the disc 82 and the ratchet 88. The yoke 94 is provided with a feed pawl 95 (Fig. 14) yieldingly pressed against the ratchet wheel 88 by a spring 96. One end of the yoke 94 is slotted at 97 (Fig. 14) to receive the flattened end of a stud 98 mounted in a carrier 99 slidable on fixed guide rods 100. A spring 101 on the lower end of one of the guide rods acts to yieldingly return the carrier and feed pawl to initial or upward position.

A plunger 102 (Fig. 15) is secured to an offset portion 103 of the carrier 99 and is provided at its lower end with a piston 104 slidable in a cylinder 105.

A spring 106 is inserted in the lower end of the piston 104 and assists the spring 101 in moving the carrier 103 and associated parts upward.

The cylinder 105 has an inlet passage 107 through which a fluid under pressure may be admitted to the upper part of the cylind-

er, thus forcing the piston 104 downward and giving the pawl 95 a feeding stroke. The passage 107 is connected to the pipe 67 (Fig. 8) which admits fluid to the piston which operates the cross feed pawls. Consequently the cross feed pawls 41 and 42 and the pawl 95 are actuated simultaneously under the control of the table dog 76 (Fig. 8).

A second feed pawl 110 (Fig. 14) is pivoted on the opposite end of the yoke 94 and engages the ratchet wheel 88 at a point substantially opposite to the pawl 95. A stop screw 111 is threaded in a lug 112 on a rearward extension of the pawl 110 and engages a shoulder on the yoke 94. A spring 113 mounted on the end of the yoke 94 engages the lug 112 and yieldingly holds the screw 111 in contact with the shoulder on the yoke 94. The screw 111 is so adjusted that when the screw engages the shoulder, the pawl 110 will be out of engagement with the teeth of the ratchet wheel 88.

A plate 114 (Fig. 16) is secured to the rear side of the pawl 110 and is provided with an angularly disposed flange 115 (Fig. 14) adapted under certain circumstances to be engaged by a positioning device mounted on the cam ring 40. This comprises a contact member 116 (Fig. 4) pivoted at 117 on a bracket 118, which in turn is secured to the side of the cam ring 40 by screws 119 (Fig. 2). The member 116 is loosely mounted on the bracket 118 but is held yieldingly in mid-position by a pair of leaf springs 120 (Fig. 4).

Operation of ratchet mechanism

The ratchet wheel 88 (Fig. 14) is provided with dwell portions 88^a at three points in its periphery. The feed pawl 95 is regularly actuated and feeds the ratchet wheel 88 a predetermined number of teeth at each actuation until the pawl 95 encounters one of the dwells or blank portions 88^a.

The rate of feed may be controlled by an adjusting screw 122 (Fig. 14) which limits the return movement of the pawl 95. During this normal operation of the ratchet wheel, the second feed pawl 110 is inoperative.

The parts are so arranged that the pawl 95 will engage one of the dwells or blanks 88^a at the end of each grinding operation, after which no movement of the ratchet wheel 88 can take place until the cam ring 40 has been rotated to a point where the contact member 116 engages the flange 115 and depresses the pawl 110 until it engages the teeth of the ratchet 88.

The springs 120 (Figs. 2 and 4) permit the member 116 to yield in either direction if movement of the pawl 110 is obstructed, but these springs 120 are strong enough to overcome the ordinary resistance of the spring 113 previously described.

The pawl 110 will then advance the ratchet wheel a sufficient distance to carry the blank

portion 88^a out from under the feed pawl 95, which will thereupon become operative and will continue to feed the ratchet wheel until the grinding operation is completed and another blank appears under the pawl 95.

It will thus appear that after the cam ring 40 has been given a definite amount of angular movement, the ratchet wheel 88 will be started and will be rotated through 120°, carrying with it the disc 82 and cam plates 90 and 92.

Table control mechanism

I will now describe the mechanism by which the table is given an increased travel after the rough-grinding has been completed and by which the grinding wheel and truing device are brought into operative relation.

Referring to Figs. 12 and 22, a ring 122^a is secured to the face of the disc or plate 82 by screws 123 (Fig. 23) extending through segmental slots 124 in the ring 122^a. The ring 122^a is thus angularly adjustable within limits on the plate 82.

The ring 122^a is provided with three equally spaced lugs or projections 125 (Fig. 22) positioned to engage a cam plate 126 secured to the upper end of a lever 127 mounted on a fixed pivot 128. A contact screw 129 is adjustably secured in a depending arm 130 of the lever 127 and engages the end of a piston valve 132 slidable in a valve cylinder 133.

A supply pipe 135 (Figs. 22 and 24) is connected to one portion of the valve chamber 133 and an exhaust pipe 136 is connected to the opposite end of the valve chamber. Ports 137 are connected through an opening 138 to a pipe 139 (Figs. 24 and 26), the other end of which is connected to the end of a cylinder 140.

A piston 141 (Fig. 26) is slidable in the cylinder 140 and is yieldingly held in the position shown by a spring 141^a. A piston rod 142 is actuated by the piston 141 and is connected through a link 143 to a member 144, loosely pivoted on the control shaft 145 by which the hydraulic table mechanism is controlled. A handle 146 is mounted on the end of the shaft 145 and is engaged by an adjustable contact screw 147 in an upward extension of the member 144.

When the lever 127 (Fig. 22) is rocked by engagement with one of the lugs 125, the piston valve 132 is pushed inward, connecting the pressure inlet 135 to the pipe 139 and thus admitting fluid under pressure to the end of the cylinder 140 (Fig. 26).

The piston 141, piston rod 142 and link 143 are thereupon moved to the left in Fig. 24, causing the contact screw 147 to engage the handle 146 and rocking the handle in the direction of the arrow *a* in Fig. 25.

When the handle and control shaft are thus rocked, certain control mechanism is set in operation by which the work table is given

an increased travel which effects a relative withdrawal of the wheel rearward from the work and into engagement with a truing device. At the same time the rate of table travel is reduced. After the wheel is dressed, the table returns to its normal limits of travel but still at reduced speed.

The control mechanism by which these operations are effected forms no part of my present invention and is fully shown and described in the said prior Drake Patent No. 1,817,180.

For the purposes of this application it is sufficient to state that rocking of the control handle 146 in the direction of the arrow *a* in Fig. 25 will cause the control mechanism to operate as above described.

It is sometimes desirable to utilize the other parts of my invention without automatically actuating the handle 146. Consequently I preferably form the link 143 in telescoping parts, normally connected by a cross-pin 148 (Fig. 24). If it is desired to disable the automatic connection to the table control mechanism, I remove the cross-pin 148 and place it in auxiliary openings 149 (Fig. 25), in which position the two parts of the link 143 telescope idly and without moving the member 144 or handle 146.

Reverse feed mechanism

After the wheel is dressed, the grinding wheel is given a predetermined number of passes over the work, the number of passes being determined by the setting of the feed pawl 95. It is then desirable to reverse the cross feed and to withdraw the wheel radially inward away from the finished surface. In this withdrawn position of the wheel, the work is allowed to reciprocate idly until the operator manually stops the machine.

In order to reverse the cross feed and to withdraw the wheel quickly from the work, it is necessary to disengage the feed pawls and to connect a relatively high speed reverse drive to the cross feed shaft.

I will first describe the mechanism by which the feed pawls are disengaged.

Referring to Figs. 5 and 6, a release lever 150 is fixed to the stud 43 to which the feed pawl 41 is also secured and on which the feed pawl 42 is loosely mounted.

The outer end of the lever 150 is provided with a face 151 (Fig. 6) underlying an arm 152 fixed to the end of a rod 153 slidably mounted in a fixed bearing 154. An arm 155 is fixed to the opposite end of the rod 153 and is provided with a cam roll 156 positioned to engage the cam 92 (Fig. 13) previously described. The cam 92 is formed with three equally spaced raised portions 92^a, as indicated in Fig. 13.

When the cam roll 156 engages one of the depressed portions of the cam 92, the arm 152 is raised by a spring to be described and

the feed pawls 41 and 42 are free to engage the ratchet wheel 33. When the roll 156 is raised by one of the high parts 92^a of the cam 92, the arm 152 is depressed and the feed pawls are raised out of engagement with the ratchet wheel 33.

I have thus provided means by which the feed pawls will be disengaged after one-third of a revolution of the control ratchet wheel 88 and parts associated therewith.

In order to render the feed pawls 41 and 42 again operative when grinding operations are to be started on a new piece of work, a lug 160 (Fig. 2) is mounted on the side of the cam 15 ring 40 in position to engage the downwardly extending arm of a lever 161 (Figs. 2 and 3) loosely mounted on the pivot stud 54.

An upwardly extending lug 162 (Fig. 3) of the arm or lever 161 engages an outer face of the arm 152. When the lug 160 engages the lever 161, it turns the lever in the direction of the arrow *b* in Fig. 3 and pushes the arm 152 and the rod 153 to the right, as viewed in Figs. 2 and 3, thus releasing the arm 150 and feed pawls 41 and 42.

A spring 164 (Fig. 2) acts to force the rod 153 yieldingly to the left in Fig. 1 and also to turn the rod 153 to hold the roll 156 in yielding engagement with the cam 92. When the rod 153 is pushed to the right by the lug 160 operating through the connections above described, the roll 156 will be carried beyond the cam 92 to the position shown in dotted lines in Fig. 5, whereupon it will swing downward until a stop screw 165 (Fig. 5) in a lug 166 on the hub of the arm 155 engages a pin 167 mounted in a fixed lug 168.

When the lug 160 passes the arm 161, the arm 152 and rod 153 will be released but return movement thereof will be prevented by engagement of the roll 156 with the side of the raised portion 92^a of the cam 92 on which the roll had previously rested.

The arm 152 will thus be held in inoperative position until the cam 92 has been rotated a sufficient distance to remove the raised portion 92^a out of alignment with the roll 156, the roll then entering the next low part of the cam but remaining inoperative until the next high part 92^a is reached.

In the usual starting operation, the ratchet wheel 33 and cam ring 40 are manually rotated in an anti-clockwise direction to move the wheel radially outward until it engages the work. By such manual rotation, the lug 160 is caused to engage the arm 161 and release the feed pawls for renewed operation without any particular attention from the operator.

Reverse cross feed drive

The reverse cross feed drive is best shown on Figs. 18 to 21. A collar 170 (Fig. 21) is fixed to a short shaft 171 rotatable in a fixed bearing 172 and having a pinion 173 engaging

the ring gear 34 (Fig. 1) previously described as mounted to rotate with the cross feed shaft 30.

A shaft 175 (Fig. 21) is mounted to rotate in alignment with the short shaft 171 and is provided with a gear 176 engaged by a wide faced pinion 177 on a countershaft 178 which may be continuously driven by a belt 179 on a pulley 180.

An elongated sleeve 182 (Fig. 21) is fixed to the shaft 175 and is slideable in a bearing 183. The sleeve 182 is provided with clutch teeth at its outer end positioned to engage similar teeth on the collar 170 previously described.

A spring 184 tends to move the sleeve 182 yieldingly toward clutch-engaging position and such movement is normally opposed by a cam roll 185 mounted on an arm 186 and engaging a flange 187 on the sleeve 182. The arm 186 is mounted on a short pivot shaft 188, to the opposite end of which an arm 189 is secured. Cam-engaging blocks 190 and 191 are secured to the end of the arm 189. The block 190 is permanently positioned thereon and the block 191 is adjustable along the arm relative to the block 190. By such adjustment, the effective width of the cam-engaging face may be varied.

The blocks 190 and 191 are positioned to engage the cam 90 previously described (Figs. 12 and 18), which cam is provided with three equally spaced recesses 90^a. When the cam blocks 190 and 191 drop into one of the recesses 90^a, the spring 184 (Fig. 21) moves the shaft 175 and sleeve 182 endwise to engage the clutch teeth and causes the pinion 173 to rotate the ring gear 34 and cross feed shaft 30 until the cam 90 has turned through a sufficient angle so that the cam blocks 190 and 191 are forced out of the recess 90^a, at which point engagement of the clutch teeth is interrupted. The amount of rotation may be determined by adjusting the block 191 toward or away from the block 190.

While the reverse movement of the cross feed shaft above described is not very rapid, it is greatly increased over the rate of feed to be obtained by the use of the feed pawls 40 and 41 and quickly removes the grinding wheel inward from finish grinding position and to a position in which the wheel clears the work, where it will be reciprocated idly until the operator stops the table movement for changing the work.

A shield 200 (Figs. 1 and 2) is mounted on the cam ring 40 to positively disengage the ratchet feed when the cam ring rotates beyond a predetermined point.

An index arm 202 (Figs. 5 and 7) may be secured to the frame member 154 and may be provided with a pointer 203 cooperating with an index line 204 on the outer face of each cam lug 125. This index line and pointer are useful when operating the machine

non-automatically, as when the link 143 (Fig. 25) is disabled by removing the pin 148. Under these circumstances, the operator may watch the index line 204 and will throw over the handle 146 (Fig. 25) as soon as the index line 204 reaches the pointer 203.

Operation

Having described the details of construction of my improved control mechanism, the method of operating the machine is as follows:—

After a grinding operation is completed, the operator throws the handle 146 (Fig. 24) to the left and brings the table to rest with the grinding wheel withdrawn from the work but in advance of the truing device. At this time the feed pawl 95 (Fig. 14) rests upon one of the blank spaces of the ratchet wheel 88 and is accordingly inoperative. Furthermore, the roll 156 (Fig. 22) rests upon one of the high points 92^a of the cam 92 and holds the feed pawls 41 and 42 inoperative, with the grinding wheel substantially spaced inward from grinding position.

After the work is changed, the operator turns the ratchet wheel 33 and cam ring 40 in an anti-clockwise direction by means of the handle in the hand wheel 37 until the grinding wheel is moved outward and engages the interior of the hole to be ground.

During this movement of the cam ring 40, the lug 160 (Fig. 2) engages the lever 161 and releases the feed pawls for renewed operation as above described.

Intermittent feeding movements of the pawls 41 and 42 then commence, advancing the ratchet wheel 33 and cross feed shaft 30 by amounts determined by the cam ring 40, the rate of feed being reduced as the grinding proceeds and approaches finish size.

After the grinding has proceeded to within a few ten-thousands of finish size, the member 116 (Fig. 2) renders the auxiliary pawl 110 (Fig. 14) operative and this pawl advances the ratchet wheel 88 far enough to remove the blank space from under the regular ratchet feed pawl 95, which thereafter continues the rotation of the ratchet wheel 88.

By such rotation, one of the lugs 125 (Fig. 22) operates through the lever 127 to actuate the piston 141 (Fig. 26) and move the handle 146 (Fig. 24) to the right, causing the table valve control mechanism to give the table an increased rearward travel and bring the wheel into the range of the wheel truing device, such increased travel being at reduced speed.

The table valve control mechanism thereafter automatically restores the travel to normal limits but still at reduced speed, and the finish grinding proceeds for a predetermined number of passes.

During this finished grinding, the roll 55 (Fig. 2) reaches the highest step of the cam ring 40 and the feed pawls 41 and 42 take

a half tooth only. The feed continues at this rate for a few passes until the shield 200 comes under the feed pawls, which then become inoperative, so that no further cross feed takes place. After a number of passes without feed, the roll 156 (Fig. 5) is engaged by a high point of the cam 92, and raises the pawls 41 and 42 from the shield 200, in which raised position they are retained until released.

The cam blocks 190 and 191 (Fig. 18) then drop into a recess in the cam 90, permitting the reverse clutch to engage, and the cross feed ratchet wheel is then reversely rotated at substantial speed to withdraw the grinding wheel quickly inward away from the finished internal ground surface.

The feed pawl 95 (Fig. 14) then encounters the next dwell or blank 88^a on the ratchet wheel 88 and the table continues to reciprocate with the parts in inoperative relation until the reciprocation is stopped by the operator for changing the work.

I am thus able to perform rough and finish grinding operations with an intervening wheel truing operation without attention by the operator, and duplicate work of great accuracy may be produced at a minimum expenditure of time and labor.

By means of the various adjustments shown the timing of the various operations can be varied, so that the relative number of passes consumed by the rough grinding and finish grinding operations may be substantially changed to meet different working conditions.

When it is desired to operate the machine semi-automatic instead of full automatic, I remove the pin 148 (Fig. 24) to the inoperative position shown in Fig. 25, thus disabling the connection to the handle 146. When operating semiautomatically, the operator watches the index line 204 (Fig. 5) and throws over the handle 146 manually when the index line 204 reaches the pointer 203. The truing mechanism is thus set in operation, causing the wheel to be dressed during an increased rearward travel of the work, after which the wheel returns automatically to its grinding range and completes the finish grinding as previously described.

With either method of operation, the workman will manipulate the handle 38 at some time during the rough-grinding operation, thereby compensating for the wear of the wheel during rough-grinding. This feature of my invention is fully described and the operation thereof explained in detail in my companion application Serial No. 485,472, filed Sept. 30, 1930.

Having thus described my invention and the advantages thereof, I do not wish to be limited to the details herein disclosed, otherwise than as set forth in the claims, but what I claim is:—

1. In a grinding machine having a table, mechanism for reciprocating said table and a control device therefor, a grinding wheel and cross feed mechanism therefor, in combination, means to actuate said cross feed mechanism to feed said grinding wheel, and mechanical control mechanism rendered operative by a predetermined operation of said cross feed mechanism and effective to cause subsequent movement of said control device and to thereby modify the table travel, said control mechanism including a ratchet wheel and a feed pawl associated therewith and means to render said feed pawl operative to turn said ratchet wheel and thereby effect movement of said control device after a predetermined actuation of said cross feed mechanism.
2. In a grinding machine having a table, mechanism for reciprocating said table and a control device therefor, a grinding wheel and cross feed mechanism therefor, in combination, means to actuate said cross feed mechanism to feed said grinding wheel, mechanical control mechanism rendered operative by a predetermined operation of said cross feed mechanism and effective to cause subsequent movement of said control device and to thereby modify the table travel, said control mechanism including a ratchet wheel and a feed pawl associated therewith and means to render said feed pawl operative to turn said ratchet wheel and thereby effect movement of said control device after a predetermined actuation of said cross feed mechanism, and means being also provided to vary the amount of feed at each actuation of said feed pawl.
3. In a grinding machine having a table, mechanism for reciprocating said table and a control device therefor, a grinding wheel and cross feed mechanism therefor, in combination, means to actuate said cross feed mechanism to feed said grinding wheel, mechanical control mechanism rendered operative by a predetermined operation of said cross feed mechanism and effective to cause subsequent movement of said control device and to thereby modify the table travel, said control mechanism including a ratchet wheel having a blank portion thereon, a regularly actuated feed pawl periodically engaging said blank portion, and an auxiliary feed pawl intermittently operative to advance said ratchet wheel to remove the blank portion from under the regular feed pawl.
4. In a grinding machine having a table, mechanism for reciprocating said table and a control device therefor, a grinding wheel and cross feed mechanism therefor, in combination, means to actuate said cross feed mechanism to feed said grinding wheel, mechanical control mechanism rendered operative by a predetermined operation of said cross feed mechanism and effective to cause
- subsequent movement of said control device and to thereby modify the table travel, said control mechanism including a ratchet wheel having a blank portion thereon, a regularly actuated feed pawl periodically engaging said blank portion, an auxiliary feed pawl, and means on said cross feed mechanism effective to render said auxiliary feed pawl operative to advance said ratchet wheel to remove the blank portion from under the regular feed pawl.
5. In a grinding machine having a table, mechanism for reciprocating said table and a control device therefor, a grinding wheel and cross feed mechanism therefor, in combination, means to actuate said cross feed mechanism to feed said grinding wheel, mechanical control mechanism rendered operative by a predetermined operation of said cross feed mechanism and effective to cause subsequent movement of said control device and to thereby modify the table travel, said control mechanism including a continuously rotated reverse feed shaft, a clutch, and cam controlled means to actuate said clutch to connect said shaft to said cross feed mechanism and to disconnect said clutch after a predetermined reverse action of said cross feed mechanism, said cam-controlled means including relatively adjustable cam blocks, by adjustment of which the period of reverse actuation of said cross feed mechanism may be variably determined.
6. In a grinding machine having a table, mechanism for reciprocating said table and a control device therefor, a grinding wheel and cross feed mechanism therefor, in combination, means to actuate said cross feed mechanism to feed said grinding wheel, mechanical control mechanism rendered operative by a predetermined operation of said cross feed mechanism and effective to cause subsequent movement of said control device and to thereby modify the table travel, and a connecting member positioned between said control mechanism and said control device, said connecting member comprising telescoping parts and a removable member for securing said parts together.
7. In a grinding machine, a cross feed mechanism including a ratchet wheel and a feed pawl, means to regularly actuate said feed pawl, means effective to raise said pawl to inoperative position, means to reversely rotate the ratchet wheel, and means to thereafter release said pawl by a predetermined manual advance rotation of said ratchet wheel.
8. In a grinding machine, a cross feed mechanism including a ratchet wheel and a feed pawl, means to regularly actuate said feed pawl, cam means effective to raise said pawl to inoperative position, means to reversely rotate said ratchet wheel, and means to thereafter release said pawl by a subse-

quent predetermined manual advance rotation of said ratchet wheel.

9. In a grinding machine, a cross feed mechanism including a ratchet wheel and a feed pawl, means to regularly actuate said feed pawl, cam means effective to raise said pawl to inoperative position, means to rotate said ratchet wheel in a reverse direction, means to thereafter disable said cam means by a predetermined manual rotation of said ratchet wheel in an advance direction, and means to thereafter restore said cam means to condition for operation.

10. In a grinding machine having a ratchet wheel and a feed pawl, a pawl lifting device comprising a rotatable cam having high and low spots, a rock shaft, an arm on said shaft, a roll on said arm engaging said cam, connections from said rock shaft to said pawl, and means to move said shaft axially to remove said cam roll from engagement with a high spot on said cam and to simultaneously render said connections inoperative.

11. The combination in a grinding machine as set forth in claim 10, in which a spring is provided effective to move said rock shaft angularly when it is shifted axially and to bring said roll in alignment with the side of the high part of said cam.

In testimony whereof I have hereunto affixed my signature.

PETER PLANTINGA.
